(57) **CLAIM**

The ornamental design for a frame in vehicle, as shown and described.

DESCRIPTION

FIG. 1 is a front perspective view of a frame in vehicle; FIG. 2 is a front elevation view of a frame in vehicle; FIG. 3 is a rear elevation view of a frame in vehicle; FIG. 4 is a right side view of a frame in vehicle; FIG. 5 is a left side view of a frame in vehicle; FIG. 6 is a top view of a frame in vehicle; FIG. 7 is a bottom view of a frame in vehicle; FIG. 8 is a rear perspective view of a frame in vehicle; and, FIG. 9 is an environmental perspective view of a frame in vehicle.

The shade lines in the Figures show contour and not surface ornamentation.

The broken lines showing portions of the design in all figures are included for the purpose of illustrating environment and do not form a part of the claimed design.

1 Claim, 9 Drawing Sheets
